CLAIM

The ornamental design for an office chair, as shown and described.

DESCRIPTION

FIG. 1 is a perspective view of an office chair showing my new design;

FIG. 2 is a front view of an office chair.

FIG. 3 is a rear view of an office chair.

FIG. 4 is a left side view of an office chair.

FIG. 5 is a right side view of an office chair.

FIG. 6 is a top view of an office chair; and,

FIG. 7 is a bottom view of an office chair.

The broken lines in the drawings depict portions of the office chair that form no part of the claimed design.
